INSULATED ELECTRICAL CONDUCTOR

Beauford H. Reeves, Pine Orchard, Conn., assignor to Rockbestos Products Corporation, a corporation of Massachusetts

Application December 16, 1932, Serial No. 647,533

6 Claims. (Cl. 173—264)

This invention relates to insulated electrical conductors and has for its object the provision of an improved article of this character. The invention is especially directed to the provision of an improved electric cable for low voltage power networks, and contemplates for such purposes a cable having effective inherent arc-quenching characteristics upon the occurrence of a short circuit or similar fault.

10 In my copending applications for Letters Patent of the United States, Serial No. 550,063, filed July 11, 1931 and Serial No. 606,617, filed April 21, 1932, I have disclosed an insulated electrical conductor in which effective arc-extinguishing characteristics are obtained by associating with the insulation surrounding the conductor a compound (such as urea) which when heated, by the occurrence of a short-circuit or similar fault, evolves a considerable volume of arc-quenching 15 gases. I have now found that a considerable proportion, if not all, of the arc-quenching compound may be advantageously placed within the hollow core of the various types of hollow core cables or conductors. Similarly, a flame-resisting material may be advantageously placed in the core of such conductors. Arc-quenching compounds are usually flame resistant, although the reverse is not always true.

20 The present invention thus comprises an insulated electrical conductor having a core containing an arc-extinguishing compound or a flame-resistant substance or both. Several types of hollow core cables or conductors are now on the market and the invention contemplates filling, to an appropriate extent, the hollow core of such a cable or conductor with an arc-extinguishing and/or flame-resisting compound. Where the compound is liquid at atmospheric temperatures it is most conveniently included in the hollow core in the form of an absorbent medium impregnated with the compound. Solid compounds may be packed in the hollow core in any appropriate manner. The insulation surrounding the metallic conductor may itself contain arc-quenching 25 and/or flame-resisting substances, so that upon the occurrence of a short-circuit or similar fault arc-quenching and/or flame resisting gases will be evolved in effective volume from both within and without the metallic conductor.

30 In the accompanying drawing

Fig. 1 shows an insulated hollow core cable embodying the invention, with its various concentric layers exposed for illustration, and

35 Figs. 2 to 12 show various types of core construction for hollow core cables or conductors.

The hollow core of the cable shown in Fig. 1 is a formed tube of copper or the like. The metallic conductor element, usually in stranded form, surrounds the hollow core. The metallic conductor is surrounded by an insulating layer of relatively high dielectric strength, such as a felted wall of asbestos impregnated with a compound consisting of about 40% chlorinated phenol and 60% gilsonite. The first insulating layer is surrounded by an arc-quenching insulating layer, such as another wall of felted asbestos impregnated with urea or other appropriate arc-quenching compound. The second insulating layer is covered with a tightly woven braid of asbestos yarn, which in turn is covered with the usual lead sheath to form the completed cable. This and other suitable forms of arc-quenching insulation surrounding the metallic conductor are described in my aforementioned patent applications.

40 In accordance with the present invention the hollow core of the cable contains an arc-quenching and/or flame-resisting compound. A convenient method of inserting the arc-quenching or flame-resisting substance within the hollow core is to saturate strands or ropes of fibrous material with a solution of the compound in an appropriate solvent thereof. Upon removal of the solvent, in the course of manufacture of the cable, the compound remains in the fibrous material. Asbestos is admirably adapted to serve as 45 the carrier for the arc-extinguishing compound because of its non-inflammability and also because it will not generate any inflammable or explosive gas at elevated temperatures.

45 Any appropriate arc-quenching or flame-resisting compound may be placed in the hollow core, such, for example, as urea, chlorinated phenols (or diphenol), antimony chloride, ammonium chloride, ammonium bromide, ammonium phosphate, chlorinated naphthalene etc. Where the compound is liquid at atmospheric and temperatures normally attained in the use of the cable, it should preferably be carried in the hollow core by a suitable absorbent medium, such as a strand or rope of asbestos or other suitable fibrous material. Even when solid at ordinary temperatures, I prefer to melt or dissolve the compound and impregnate an absorbent or porous medium therewith, as the means of inserting and retaining the compound in the hollow core. Compounds which are solid at ordinary temperatures may, on the other hand, be inserted and retained in the core in various other ways.

50 Upon the occurrence of a short-circuit or other fault developing a sufficiently high tem- 55

perature to damage the metallic conductor, effective volumes of arc-quenching or flame-resisting gases such as ammonia will be evolved by the compound in the hollow core of the cable. The 5 volume of gases thus evolved may be adequate to quench any arc or flame, but in any case will supplement similar gases evolved from the insulation surrounding the conductor, thereby requiring less external arc-quenching insulation. 10 Thus, by the invention, the central cavity of hollow core cables is put to profitable and advantageous use and the amount of external arc-quenching insulation which would otherwise be required is reduced. 15 The invention may be embodied in any type of hollow core cable. The aim in the hollow core cable is to concentrate the metallic conductor in that part of the cross-section of the finished cable where it will carry the most current. In order 20 to accomplish this aim various means are used to produce a hollow core around which the copper or other metallic wires are stranded or cabled. In Figs. 2 to 6 of the drawing, I have illustrated certain types of core construction in which the 25 present invention may be advantageously embodied.

Figs. 2, 3 and 4 illustrate a coil spring type of hollow core construction, which may be made up of round copper wire, helically wound with 30 close turns to produce a hollow core, or with flat or rectangular strip material wound in the same manner.

In Figs. 5 and 6 the hollow core is in the form of a twisted I-beam of copper or the like. The 35 metallic rod, of I-beam section, is twisted (lightning rod fashion) so as to provide a substantially circular form against which the wires of the metallic conductor are cabled. The cavity on each side of the I-beam is filled with an arc-quenching and/or flame-resisting compound in 40 accordance with the present invention.

The hollow core illustrated in Figs. 7 and 8 is made from a flat strip of copper rolled around to form a tube as it goes into the cabling machine.

45 The hollow core shown in Figs. 9 and 10 is made of copper strips having a ship-lap edge

placed in longitudinal engagement with a slight spiral lay to provide flexibility.

The core illustrated in Figs. 11 and 12 consists of a rope of fibrous material, such as a manila rope or an asbestos rope. In this case the fibrous rope, constituting the core of the cable, is utilized 5 as the carrier for the arc-extinguishing or flame-resisting compound.

The invention may of course be embodied in other types of hollow core construction. In any case, the advantages of the invention are attained by appropriately incorporating an arc-extinguishing and/or flame-resisting substance in the cavity of a hollow core cable or conductor, as for example by placing the substance directly in the cavity or 10 by putting in a fibrous filler saturated or impregnated with the substance. 15

I claim:

1. An insulated electrical conductor having a hollow core substantially filled with a fibrous material impregnated with an arc-extinguishing compound. 20
2. A hollow core electric cable having a fibrous filler in the cavity of the hollow core thereof, and an arc-extinguishing compound associated with 25 said fibrous filler.
3. An insulated electrical conductor having a hollow core containing asbestos impregnated with an arc-extinguishing compound. 30
4. An insulated electrical conductor having a hollow core containing one or more flame-resisting and arc-extinguishing substances selected from the group consisting of urea, chlorinated phenols, chlorinated diphenols, chlorinated naphthalene, ammonium halides, and ammonium 35 phosphate.
5. An insulated electric cable having a hollow core containing a fibrous filler impregnated with a liquid capable of evolving at elevated temperatures an arc-extinguishing gas in effective volume. 40
6. An insulated electric conductor having a hollow core containing a substance capable of evolving ammonia in effective volume at elevated temperatures. 45
